UNITED STATES PATENT OFFICE.

ANTON MARIUS CRAMER, OF MONTREAL, QUEBEC, CANADA.

WALL CONSTRUCTION.

Application filed January 16, 1925. Serial No. 2,853.

To all whom it may concern:

Be it known that I, ANTON MARIUS CRAMER, a subject of the King of Denmark, and residing at the city of Montreal, in the Province of Quebec, in the Dominion of Canada, have invented a new and useful Wall Construction, of which the following is the specification.

The invention relates to wall construction, as described in the present specification and illustrated in the accompanying drawings that form part of the same.

The invention consists essentially of the novel features of construction pointed out broadly and specifically in the claims for novelty following a description containing an explanation in detail of an acceptable form of the invention.

The objects of the invention are to eliminate the bad effects of open joints in cement concrete or other block walls and thereby insure warmth and security in the interior of a house or other building; to increase to the utmost limit the air spaces between inner and outer blocks of the wall; and generally to provide an economical, durable and efficient construction.

In the drawings Figure 1 is an elevation of the wall construction.

Figure 2 is a vertical sectional view on the line 2—2 in Figure 1.

Figure 3 is a horizontal sectional view on the line 3—3 in Figure 1.

Figure 4 is a horizontal sectional view on the line 4—4 in Figure 1.

Figure 5 is a view of an outer top wall block.

Figure 6 is a top plan view of an outer wall block.

Figure 7 is an enlarged detail of an inner wall block.

Figure 8 is a top plan view of an inner wall block.

Figure 9 is a sectional view of a corner of the wall construction.

Like numerals of reference indicate corresponding parts in the various figures.

Referring to the drawings, the construction of the wall is begun by placing the starting course, formed by the blocks 10 and 11 on to the prepared foundation 12. These blocks are permanently secured to each other at 13 and form a rigid base, and have the tongue 14 adapted to be inserted into the groove of another block laid thereon.

The main front blocks 15 are formed with the tongue grooves 16 and are backed on the used surfaces with asphalt 17 and tar paper 18, the latter overlapping at one end to cover the joint with the next block.

The intermediate blocks 19 are similarly formed to the main blocks 15 having the tar paper and asphalt but in place of the grooves 16 they have the tongues 20 fitting into said grooves 16, each of the blocks 19 overlapping two blocks 16 or in other words crossing the joint.

The inner blocks 21 are formed with the grooves 22 and the central hollow abutments 23 and end abutments 24 faced with the building cotton 25 secured by asphalt or other adhesive. These abutments engage the front wall blocks 15 on the tar paper side and the cotton faced central abutments 23 cover the joints of the front blocks.

The locking blocks 26 and 27 are introduced at the front and the rear respectively and are formed of face portions 28 and 29 having the tongues 30 and 31 and 32 and 33 and the interlocking inner portions 34 and 35, which fit into one another and are lined with building cotton 36 and 37 at the meeting faces and also at 38 and 39 to meet the cotton covered backs 40 and 41 of the face portions 28 and 29. The interlocking inner portions of the locking blocks 26 and 27 are longer than the face portions 28 and 29 thereby engaging the backs of the contiguous blocks.

The locking blocks are introduced at intervals preferably in the centres of the main blocks and in the same courses as the intermediate blocks and effectually hold the inner wall blocks to the outer wall blocks.

The construction of a corner is shown at 42 in Figure 9, but it is obvious that various turns and different angles and features of the building may be accommodated and still contain the invention, which is the peculiar form of the blocks and the provision for tight joints, as well as the security afforded by the locking means.

The advantages of this wall are manifest to the practical man for the many troubles incident to wall constructions are taken care of and a close wall provided for all climatic conditions as it will insure warmth in cold weather and be cool in warm weather and at the same time be steadfast in its position and impervious to the elements.

What I claim is:—

1. In wall construction, a plurality of main blocks, in courses, a plurality of intermediate blocks in courses, between said main blocks and forming therewith a front to the wall, a plurality of main rear blocks having abutments meeting the joints of the front blocks, a plurality of intermediate rear blocks and locking blocks having fabric meeting faces, said blocks forming front and rear blocks and containing interlocking inner portions and introduced in said intermediate courses.
2. In wall constructions, a plurality of main blocks with asphalt and tar paper backs forming an end overlap, a plurality of intermediate blocks in courses, between said main blocks and forming therewith a front to the wall, a plurality of main rear blocks having abutments meeting the joints of the front blocks, a plurality of intermediate rear blocks and locking blocks front and rear having interlocking inner portions and introduced in said intermediate courses.
3. In a wall construction, a plurality of main blocks in courses, a plurality of intermediate blocks in courses between said main blocks and forming therewith a front to the wall, a plurality of main rear blocks having a fabric backing and abutments meeting the joints of the front blocks, a plurality of intermediate rear blocks and locking blocks front and rear having interlocking inner portions and introduced in said intermediate courses.
4. In wall construction, a plurality of main blocks in courses, a plurality of intermediate blocks in courses between said main blocks and forming therewith a front to the wall, a plurality of main rear blocks having central hollow abutments and end abutments meeting joints of the front blocks, a plurality of intermediate rear blocks and locking blocks front and rear having interlocking inner portions and introduced in said intermediate courses.
5. In a wall construction, a plurality of main blocks in courses, a plurality of intermediate blocks in courses between said main blocks and forming therewith a front to the wall, a plurality of main rear blocks having central hollow abutments with fabric meeting surfaces, a plurality of intermediate rear blocks and locking blocks front and rear having interlocking inner portions and introduced in said intermediate courses.
6. In a wall construction, a plurality of main blocks in courses, a plurality of intermediate blocks in courses, between said main blocks and forming therewith a front to the wall, a plurality of main rear blocks having central hollow abutments with fabric meeting surfaces, a plurality of intermediate rear blocks and locking blocks front and rear having interlocking inner portions and introduced in said intermediate courses.

Signed at Montreal, Canada, this 10th day of January 1925.

ANTON MARIUS CRAMER.
